GEAR CASING.

Application filed October 4, 1924. Serial No. 741,551.

Fig. 1 is a partial side view of an electric locomotive equipped with a gear casing embodying our invention; Fig. 2 is a transverse vertical section thereof showing our improved gear casings on both sides of the locomotive; Fig. 3 is a detail section showing the means for attaching the two sections of the casing together; Fig. 4 is a detail of a spacing washer; Figs. 5 and 6 are, respectively, perspectives of the main inner and outer portions of the casing; and Fig. 7 is a perspective of the cap or upper half of the covering for the motor pinion.

Our invention relates to the gear wheel casings intended to contain a pair of gear wheels, and has for its object the production of a gear case substantially oil tight, of low cost, minimum weight, and which may be easily handled during removal or replacement. To this end we have constructed a gear case mainly of sheet metal so related that the gears and shafting may be taken down without requiring the removal of both of the main sections of the casing from its support. Our invention also comprises the various features which we shall hereinafter describe and claim.

Referring to the drawings, the numeral 1 indicates the motor shaft to the ends of which 30 motor pinions 2 are affixed. Meshing with the pinions 2 are the gear wheels 3 mounted on the ends of the jack shafts 4. Power from the motor 1^a is transmitted to the driving wheels through the crank pins 5 on the gears 3 and the coupling rods 5^a.

The casing about the pinion 2 and gear 3 comprises the inner plate 6, the outer cover 7 and the pinion cap 8. The plate 6 is preferably shaped out of a sheet of wrought metal to which the supporting lugs 6^a are riveted. Upon the lugs 6^a are the shoulders 6^b by which the plate 6 rests on the frame 15 when the case is being placed in position. The center of the plate 6 is cut out at 6^c to form a running fit against the collar 3^a, which is on the inner face of the gear 3. At the bottom the plate 6 is cut away to permit the lowering and removal of the jack shaft. This opening when the case is in use is closed by a plate 6^d in order to make the casing dust proof and oil tight. The upper portion of the plate 6 has a semi-circular recess 6^e for the motor shaft 1. The plate 6 is attached to the motor frame by means of bolts 9 which seat in the bolt holes 6^b of the plate and are threaded into the frame 15. The plate 6 is maintained in properly spaced relation to the frame 15 by means of the washers 10, preferably made of two pieces bolted together to permit their ready application upon or removal from the bolts 9. Upon either side of the closure plate 6^d, and substantially at right angles to the plate 6, are flanges 6^f, which form a supporting bearing for the outer casing 7 and also serve to position it accurately.

The outer casing 7 is of dish shape and has in its upper portion a semi-circular recess 7^a for the motor pinion 2. The upper edges 7^b of the recess 7^a are flanged to provide a bolting bearing for the pinion cap 8. A grooved half ring 7^c is riveted at the outer side of the recess 7^a for reception of a closing plate 11 which with the outer wall of the cap 8 forms a complete closure around the outer end of the motor shaft 1. To make the closure oil and dust tight, a felt ring 12 secured by a washer 13 may be placed over the outer end of the shaft 1. The central portion of the outer casing 7 is cut out at 7^d to make a running fit against the driven gear collar 3^b and forms a dust and oil proof joint at this surface.

Secured about the inner edge 7^e of the casing 7 is the reinforcing ring 7^f, the outer edge of which forms an undercut shoulder 7^g for 85 the hook bolts 14 mounted near the periphery of the plate 6 in the holes 6^g. The pinion cap 8 has a flange 8^a shaped to bear against the end of the motor bearing 16 and is secured thereto by a stud passing through the lug 8^b. The cap 8 is also attached to the flanges 7^b of the casing 7 by bolts extending through its flanges 8^c. An opening 8^d is provided in the top of the pinion cover 8 to permit ready inspection of the pinion and afford a place to apply a lubricant.

With a gear casing embodying our invention the jack shaft 4 may be removed without difficulty. To effect this the pinion cap 8 is first taken off and then the bolts 14 are loosened so as to remove the outer casing 7. Next the bolts 9 are taken out, the washers 10 disengaged therefrom, and the inner bottom plate 6^d removed. As the plate 6 is then resting on its shoulder 6^b, it is next tilted at its bottom toward the frame 15 until the edge of the recess 6^e clears the lower circumferential edge of the gear collar 3^a, and then, when the jack shaft 4 has been withdrawn along its own axis to clear the frame 15, the gear 3

and shaft 4 may be dropped straight downward leaving the inner plate 6 suspended from its shoulders 6⁹.

It will therefore be seen that the operation of removing or replacing a jack shaft or gear is extremely simple with gear cases embodying our invention, and that because of the simplicity of our improved construction it may be made at low cost and forms as well an extremely effective and reliable protection to gears.

The terms and expressions which we have employed are used as terms of description and not of limitation, and we have no intention, in the use of such terms and expressions, of excluding any mechanical equivalents of the features shown and described, or portions thereof, but recognize that various structural modifications are possible within the scope of the invention claimed.

What we claim is:

1. A gear casing comprising an inner and an outer part enclosing between them a driven gear, a support, bolts securing the casing to the support, and centering means for maintaining the parts in operative relation to each other, the inner part having in its bottom portion a removable section to permit withdrawing the gear and shaft when the outer part has been removed.

2. In a railroad vehicle, the combination of a shaft; a gear wheel mounted thereon, having on each side a projecting concentric collar and a housing, enclosing the gear wheel, comprising two members, one member constituting a cover provided with a circular opening, the edges of which make a substantially oil proof fit with one of the collars of the gear wheel, said member comprising a portion removable to provide an opening through which the shaft may be withdrawn cross-axially of the member, the other member having a circular opening, the edges of which make a substantially oil proof fit with the other collar of the gear wheel, said last mentioned member having a portion overlying the rim of the gear wheel, and making a substantially oil proof joint with the cover member.

3. In a railroad vehicle, the combination of a shaft; a gear wheel mounted thereon, hav-

ing on each side a projecting concentric collar, and a housing, enclosing the gear wheel, comprising two members, one member constituting a cover provided with a circular opening, the edges of which make a substantially oil proof fit with one of the collars of the gear wheel, the other member having a circular opening, the edges of which make a substantially oil proof fit with the other collar of the gear wheel, said last mentioned member having a portion overlying the rim of the gear wheel, and making a substantially oil proof joint with the cover member; one of the members having a portion removable to provide an opening through which the shaft may be withdrawn cross axially of the member.

4. In a railroad vehicle, the combination of a shaft; a gear wheel mounted thereon, having on each side a projecting concentric collar, a vehicle frame; and a housing, enclosing the gear wheel, comprising two members, one member constituting a cover provided with a circular opening, the edges of which make a substantially oil proof fit with one of the collars of the gear wheel, the other member having a circular opening, the edges of which make a substantially oil proof fit with the other collar of the gear wheel, said last mentioned member having a portion overlying the rim of the gear wheel, and making a substantially oil proof joint with the cover member; one of the members having a portion removable to provide an opening through which the shaft may be withdrawn cross axially of the member, said last mentioned member having means adapted to hook on to the vehicle frame to support the member during withdrawal of the gear and shaft.

5. In a railroad vehicle, the combination of a shaft; a gear wheel mounted thereon; and a casing, for containing oil, enclosing the gear wheel, and comprising two members enclosing opposite sides of the gear wheel, and encircling the shaft; one of the members having a bottom portion removable to provide a space through which the shaft may be moved cross axially out of the member.
